UNITED STATES PATENT OFFICE.

RICHARD H. RICE, OF LYNN, MASSACHUSETTS, ASSIGNEE TO GENERAL ELECTRIC COMPANY, A CORPORATION OF NEW YORK.

GOVERNOR FOR CENTRIFUGAL AIR-COMPRESSORS.

1,080,717.

Specification of Letters Patent.

Patented Dec. 9, 1913.

Application filed April 15, 1910. Serial No. 555,613.

To all whom it may concern:

Be it known that I, RICHARD H. RICE, a citizen of the United States, residing at Lynn, county of Essex, State of Massachusetts, have invented certain new and useful Improvements in Governors for Centrifugal Air-Compressors, of which the following is a specification.

This invention relates to mechanism for governing the volume of fluid discharged by a centrifugal compressor, and it constitutes a modification of the similar invention patented to me on April 27, 1909, No. 919,953. In that patent, the governor consists of a counterweighted float located in an enlargement of the conduit conveying air to the compressor. In the present instance, the float is a plain disk located in a straight portion of said conduit, thereby affording a much simpler construction of these parts.

In the accompanying drawing, Figure 1 is an end view of a turbine driven air compressor embodying my invention, and Fig. 2 is a side elevation of the same.

1 indicates the casing of the centrifugal compressor and 2 the impeller thereof, the latter being mounted on the main shaft 3 supported by suitable bearings carried by the bed plate 4. The casing of the compressor is also supported by the bed-plate, which in addition carries a turbine 5, of any suitable construction; as here shown it is of the well-known Curtis type. The bucket wheel is mounted on the main shaft 3. Steam is admitted to the turbine by the pipe 6 containing the shut off valve 7. Between the shut off valve and the turbine is a regulator or throttle valve 8 which also controls the passage of the steam to the turbine. Driven by the main shaft of the turbine is a speed responsive device comprising a collar 9 that is fast to the bevel gear 10, and the latter meshes with a bevel gear 11 carried by a low speed shaft that is driven by the main shaft.

A vertical spindle 12 slides in the collar 9 and carries a collar 13, the latter being in turn connected to the centrifugally acting weights 14, so that as the speed of the turbine increases and the weights move outwardly the spindle 12 will be depressed. To the lower end of the spindle 12 is attached one end of the lever 15, to whose opposite end is attached the rod 16. To the lever 15 at a point between its ends is pivoted the

stem 17 of the throttle valve 8. The upper end of the rod 16 is connected to an arm 18 on a rock shaft 19. A second arm on said shaft is connected by the link 20 to an arm 21 on a rock shaft 22, which carries another arm 23 pivoted to the upper end of a rod 24 whose lower end is attached to the disk 25, which in this instance takes the place of the float shown in my aforesaid patent. The rod 24 is guided in a spider 26 inserted in the conduit 27. The disk is kept in a normal position by a spring 28 abutting at its lower end on a collar 29 on the rod 24 and at its upper end against a screw plug 30 surrounding the rod and adjustable in a nut 31 mounted in an opening in the top of the elbow 32 connecting the conduit with the pipe 33 which communicates with the compressor. The outlet of the compressor is at 34.

It will be observed that the portion of the conduit in which the float or disk 25 is located is straight, being in fact a portion of the preferably cylindrical regular conduit, and not a special section made therefor, as in my former patent. The theory of operation is, however, the same. If the volume of fluid discharged by the compressor decreases, the disk 25 will be lowered slightly due to the spring 28 and to gravity, and in so doing it will raise the rod 16 and thereby lift the stem 17 of the throttle valve, increasing the supply of steam to the turbine. This causes the speed of the compressor to increase and the pressure of the air discharged will also increase until the volume is restored to normal. An increase of this volume above normal will produce an opposite effect upon the throttle valve and slow down the turbine and compressor. The centrifugal speed governor, connected to the other end of the lever 15, also exerts a control upon the turbine, tending to slow it down when it runs too fast, and vice versa.

In my aforesaid patent, the float is counterbalanced by a weight, so as to permit it to be adjusted for different outputs. I replace the weights by the spring in the present invention, which by means of the screw plug can be adjusted very accurately for any given output.

It is to be noted that my improved governing mechanism will deliver a constant volume of air at the outlet, irrespective of its pressure.

For a discussion and explanation of the theory upon which the disk or float operates in response to a change in the volume of the air passing through the inlet of the compressor, reference may be had to my aforesaid patent.

My improved mechanism has the very important advantage that it can be readily adjusted in so far as its governing characteristics are concerned. By using a flat disk in a cylindrical pipe in the manner stated, the spring may be varied as to its scale and also as to its tension or compression thereby varying the governing characteristics without appreciably altering the governing force.

It will be seen that my improved mechanism possesses the marked advantage of great flexibility of adjustment, and this without disturbing the float or the cylindrical conduit that contains it.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:

1. The combination with a centrifugal apparatus for imparting pressure to a fluid, of a motor for driving it, a mechanism for controlling the speed of said motor, a fluid conveying conduit having a straight portion, a float located in said portion of the conduit, means including a rod for transmitting the movements of said float to the controlling mechanism and an adjusting spring that acts on said rod to vary the action of the float.

2. The combination with an air compressor, of a motor for driving it, a straight cylindrical-walled conduit conveying air to said compressor, a connection between the conduit and the compressor, a float located in the cylindrical conduit, a rod connected

to the float and extending through said connection, a spring that surrounds the rod and is located in said connection, means supported by the connection and external to it for adjusting the effect of the spring, and a regulator for the motor which is sensitive to the movements of said float and rod.

3. The combination with an air compressor, of a motor for driving it, a straight vertical conduit for conveying air to said compressor, a float located in said conduit, a spring for opposing the upward movements of said float, means for adjusting the spring and a regulator for the motor which is responsive to movements of said float.

4. The combination with an air compressor, of a motor for driving it, a conduit through which the air acted upon by the compressor passes, said conduit having a straight sided portion, a device located in said portion and moved by the fluid flowing through it, a spring opposing movement of the device in one direction, means for adjusting the spring, a regulator for the motor, and means for causing movements of the device to modify the position of the regulator.

5. The combination with an air compressor, of a motor for driving it, a conduit through which the air acted upon by the compressor passes, said conduit having a straight cylindrical portion and an elbow connected thereto, a float located in the straight portion, an axially movable rod on one end of which the float is mounted, the other end of said rod extending outwardly through the wall of the elbow, an adjustable and removable abutment mounted on the wall of the elbow and through which the rod passes, an abutment on the rod, a spring having its ends in engagement with said abutments, a regulator for the driving motor, and means connecting the outer end of the rod with the regulator.

In witness whereof, I have hereunto set my hand this thirteenth day of April, 1910.

RICHARD H. RICE.
